US00D877565S

(12) **United States Design Patent** (10) **Patent No.:** **US D877,565 S**
(45) **Date of Patent:** **** Mar. 10, 2020**

(54) **CONTAINER WITH A CAP AND FILTER ASSEMBLY**

(71) Applicant: **HYDROS BOTTLE, LLC**, San Francisco, CA (US)

(72) Inventors: **David Michael Pehar**, Willoughby, OH (US); **Trevor L. Jackson**, Kirtland, OH (US); **Robert Craig Allen**, Richmond Heights, OH (US); **Marc Louis Vitantonio**, South Russell, OH (US); **Jess Paul Carlson**, Bainbridge, OH (US); **Winston Ibrahim**, Tiburon, CA (US); **Jon Holland**, San Rafael, CA (US)

(73) Assignee: **HYDROS BOTTLE, LLC**, San Francisco, CA (US)

(**) Term: **15 Years**

(21) Appl. No.: **29/598,232**

(22) Filed: **Mar. 23, 2017**

(51) LOC (12) Cl. **07-01**

(52) U.S. Cl.

USPC **D7/510**; D7/511; D7/532

(58) **Field of Classification Search**

CLAIM

The ornamental design for container with a cap and filter assembly, as shown and described.

DESCRIPTION

FIG. 1 is a front, top, right side perspective view of a container with a cap and filter assembly showing our new design.

FIG. 2 is a rear, bottom, left side perspective view thereof.

FIG. 3 is a right side plan view thereof.

FIG. 4 is a left side plan view thereof.

FIG. 5 is a front view thereof.

FIG. 6 is a rear view thereof.

FIG. 7 is a top view thereof; and,

FIG. 8 is a bottom view thereof.

The broken lines in the drawings depict portions of the container with cap and filter assembly that form no part of the claimed design.

1 Claim, 7 Drawing Sheets
